IRONING DEVICE

Simon Deutsch, Milwaukee, Wis.

Application February 20, 1936, Serial No. 64,804

5 Claims. (Cl. 38—30)

This invention relates to ironing devices and it has among its objects an improved ironing device enabling fast ironing of flat work, such as sheets and towels, as well as clothes and similar articles which cannot be ironed or are very difficult to iron with the ordinary mangle ironers and thus, ordinarily, require slow hand ironing.

The foregoing and other objects of the invention will be best understood from the following 10 description of exemplifications thereof, reference being had to the accompanying drawings in which:

Fig. 1 is an elevational view of an ironing device exemplifying the invention;

15 Fig. 2 is a plan view of Fig. 1;

Fig. 3 is a sectional view of the lifting mechanism of Fig. 1 along line 3—3 of Fig. 2;

Fig. 4 is an elevational view of the ironing device in folded upstanding position;

20 Figs. 5 to 8 are detailed cross sectional views of the leg brackets of the device;

Fig. 9 is a view similar to Fig. 1 of a modified ironing device;

25 Fig. 10 is an elevational view partially in section of the iron and its support when the iron rests on the board;

Fig. 11 is a partially sectional view of the iron support in the lifted position;

30 Fig. 12 is a top view partially in section of the iron and its support;

Fig. 13 is a detail view of the iron clasp;

Fig. 14 is a view similar to Fig. 1 illustrating another modification of the device;

35 Fig. 15 is a partially sectional view similar to Fig. 1 illustrating a further modification of the device;

Fig. 16 is a detailed sectional view of the foot lever hinge of Fig. 15;

Fig. 17 is a view similar to Fig. 1 of a further modification of the device; and

40 Fig. 18 is a cross sectional view of the actuating mechanism of the device of Fig. 17 along line 18—18 of Fig. 17.

Since in a majority of households the laundry is washed and ironed at home, many efforts have been made in the past to supply washing and ironing machines to eliminate the drudgery connected with such work.

The ironing device of the present invention 50 enables fast high-quality ironing of all laundry and clothes that required hand ironing in the past as well as fast ironing of flat work while relieving the operator of the fatigue and strain incident to hand ironing.

55 In accordance with the invention, a heavy iron,

having a weight of about 10 pounds which would be too heavy for ordinary use, is held by a cantilever arm support in a lifted floating condition making it easy to move it to any portion of the ironing board and apply it easily to ruffles, collars, cuffs and similar parts of the clothing which ordinarily require hand ironing. By a special mechanism, the cantilever arm lifts the iron off the board the instant the ironing work on a piece is finished. No manual effort is needed to lift the iron or to 10 place it on the board while the piece that is being ironed is folded or rearranged on the ironing board. The complete ironing device can be folded up and stored away in a closet like an ordinary ironing board. The cord which supplies 15 electric current to the iron is kept out of the way during the ironing operation and the iron does not become entangled in the cord incident to the ironing.

In Figs. 1 to 12 is shown one embodiment of the 20 invention. It comprises an ironing board 30 supported by front legs 31 and rear legs 32 attached to the underside of the board by bearings 33 and 34. As shown in Figs. 4 to 8 the front legs 31 may form parts of a single tubing having a transverse 25 connecting member 36 extending through the bearings 33 and provided with guide pins 37 fitting into longitudinal slots 38 of the bearings to permit transverse shifting of the connecting member 36 between transverse slots 39, 40 extending 30 from the opposite ends of the longitudinal slot 38. By bringing the guide pins 37 into engagement with the transverse slots 39, the front legs may be tilted in the bearings 33 to the position shown in Fig. 1 in which the legs support the table in horizontal position. To fold the front legs, the front 35 legs 31 are tilted till the guide pins 37 are aligned with the longitudinal bearing slots 38, whereupon the legs are shifted transversely till the pins 37 engage the transverse slots 40, in which position 40 the legs may be folded as shown in Fig. 4. The front legs 31 may be locked in the folded position, for instance, by bolts 42 slidably mounted in brackets 43 attached to the bottom of ironing board in the way shown in Fig. 4, so that only 45 upon pushing the bolts to the inward dotted line position 42' the legs may be unfolded to the position shown in Fig. 1.

As shown in Fig. 6, the rear leg-bearings 34 have transverse slots 45 engaged by transverse 50 pins 46 extending through the connecting member 47 of the rear legs 32 to permit folding of the legs parallel to the board as shown in Fig. 4, or unfolding the legs to the position where they support the board in horizontal position as shown in Fig. 1. 55

On the underside of the ironing board near the front edge of its rear end is mounted a lifting mechanism 51 which is attached to the board by a suitable bracket 50. The lifting mechanism has a 5 sleeve 52 which serves as a rotary support for a downward extension 53 of a horizontally projecting cantilever arm 54 provided with a forearm 55 which swings freely on the hinge joint 56 and carries between prongs 57 a heavy iron 58. The 10 rear portion of the forearm 55 is curved near its hinged junction and is shaped and articulated to permit easy swinging of the iron supported at the end of the forearm 55 to any place above and adjacent to the ironing board.

15 As shown in detail in Fig. 3, the lifting mechanism 51 consists of two channel-shaped links 61 which are movably attached through pins 64 to vertical channel members 65, 66 extending from the supporting bracket 50 and from the supporting sleeve 52, respectively, for guiding the sleeve 52 with the cantilever arm 54 in a vertical direction.

From the supporting sleeve 52 extends an inward lifting arm 68 to which is joined a downwardly extending rod 69 having a foot pedal 70. A tension spring 71 having its upper end 72 attached to the underside of the ironing board 30 and its lower end 73 to a lug on the foot rod 69 pulls the arm and the lifting mechanism to the 30 upper position shown in Fig. 1 and holds the arm and the iron in this lifted position. The iron may be readily lowered, and placed with its full weight on the ironing board by applying to the foot pedal 70 suitable foot pressure sufficient to 35 overcome the pressure of the tension spring 71 which tends to return the lifting mechanism and the iron to the upper position. For storing, the foot rod 69 with the tension spring may be tilted around the connecting pin 74 to the folded position as shown in Fig. 4.

40 To reduce the foot pressure required to hold the pedal 70 in the downward position during ironing, the lifting mechanism may be provided with a toggle arrangement shown in Fig. 9. It 45 comprises two toggle links 75 connected between the actuating arm 68 and the underside of the board 30 and a spring 94 which urges the links to the broken position. Once the foot pedal 70 has been brought by foot pressure to the downward position shown in Fig. 9, the two toggle links 50 are in alignment and in this position form a substantially straight rod which opposes the force of the spring 71 tending to lift the iron, and thus assist in holding the lifting mechanism and iron 55 in the downward position. However, since the two aligned toggle links 75 are in unstable equilibrium, they remain aligned only as long as they are assisted by a small foot pressure in remaining in substantially aligned position. The moment 60 the foot pedal 70 is released, the toggle spring 94 breaks the alignment of toggle links 75, whereupon the combined force of the tension spring 71 and the toggle spring 94 instantaneously raise the arm 68 and thus lift the iron from the work.

65 The construction of the iron 58 and its support on the forearm 55 are shown in detail in Figs. 10 to 14. To secure fast ironing action, a heavy iron, of a weight of about 10 pounds, for instance, is used. To enable comfortable handling of the 70 iron while ironing, the iron handle 77 with its bracket 78 are held at a distance from the hot body of the iron by a spacer sleeve 79 surrounding a bolt which connects the bracket to the iron body. Thus the handle as well as the bracket 75 are at all times maintained at a comfortable

low temperature notwithstanding the high temperature of the large iron body.

The sleeve 79 is provided with a protuding ball member 80 which is engaged by an inner socket surface of a supporting collar 81 fitting into the 5 annular opening between the end prongs 57 of the supporting forearm 55, the collar socket being locked in place by a wing screw 82 as shown in Fig. 12. The cooperating surfaces of the ball member 80 and the collar 81 are so shaped that 10 on raising the arm 55 to lift the iron, the bottom surface of the iron is automatically brought to horizontal position in which its entire body is held at a distance from the work lying on the ironing board. As shown in Figs. 10 and 11, substantial clearances are provided between the cooperating surfaces of the supporting ball 80 and the collar 81 to permit tilting of the iron while it rests on the work and while it is carried by the arm in floating position.

15 The iron may be removed from the supporting arm 55 while the iron rests on the ironing board by lifting the unloosened supporting collar 81 from its seat between the arm prongs 57 to the upper position shown in Fig. 11, while pressing down the lifting arm 55 till the opening between the prongs 57 provides a free path for sliding the iron with the lifted collar 81 from its space between the prong arms.

20 Alternatively, as shown in Fig. 13, one of the 30 prongs 57 may be provided with a link 83 for closing the opening between the prongs and locking the iron in place, the link being held in locked position by a spring pressed latch 84 permitting ready opening of the link and removal of the 35 iron.

25 The ball member support 80 of the iron serves 40 also as an automatic signalling device for indicating to the operator that the full weight of the iron rests on the ironing board, thus giving 45 him a positive indication that the iron is in the position required for efficient ironing. This signalling action is obtained through the motion of the ball member 80 from the position in which it is hidden within the collar socket of the support as shown in Fig. 11 to the position where 50 it protrudes above the collar when the iron rests on the ironing board as shown in Fig. 10. While the iron is in the lifted position shown in Fig. 11, the ball member 80 is hidden from the view of 55 the operator, but the instant the supporting arm 55 lowers the iron and brings it on the board, the downward motion of the arm brings the collar with the socket below the upper level of the ball member 80, exposing it to the view of the operator, and thus signals to the operator that the iron is in its efficient operating position for ironing. To increase the signalling action of the ball support, the exterior ball surface may be made of a distinctive color, for instance, red.

60 The special shape and other features of construction of the large iron which make it suitable for doing special ironing work at a rapid rate are shown in Figs. 10 and 12. The pointed nose of the iron body and its side edges are beveled 65 under an angle of about 45° and have a sufficient reach for entering under buttons, folds, sleeves, collars and similar parts of the articles that are difficult to reach with ordinary irons.

65 Electric heating current is led to the iron 70 through a terminal socket 85 connected by leads 86 extending through a bracket pocket 87 and a conduit 88 to the heating elements and the automatic temperature control embedded in the main iron body 58. The heating current is supplied 75

to the terminals of the socket 88 by means of a cord plug 89 connected to the end of a flexible cord 91 which is led through the interior of the hollow forearm 55 and main supporting arm 52 to a suitable wall plug. By mounting the terminal socket high above the hot iron body, the contact members of the socket and the plug are maintained at a relatively low temperature and are protected against the quick deterioration to which the high temperature of the iron body subjects the contact terminals and lead connections of ordinary irons. By housing the long cord 91 leading from the cord plug in the interior of the freely swinging cantilever arm, the cord is not dragged over the board, entanglement of the iron in the cord is eliminated, and the burning of the cord due to accidental contact with the hot iron body is prevented.

As shown in Figs. 2 and 4 the supporting bracket 65 which supports the lifting mechanism is mounted at an angle against the longitudinal direction of the ironing board and the lifting arm extends in the same angular direction. Since the vertical forces which act on the supporting mechanism are at a maximum when the articulated supporting arms 54 and 56 are stretched to support the iron over the front end of the board, this angular mounting of the support secures an effective balance between the forces acting on the support, and reduces to a minimum the friction and wear of the pins and journaling surfaces which guide the motion of the various elements of the device.

By mounting the lifting mechanism with the sleeve 52 near the front edge of the board, the articulated members of the cantilever support do not have to move far out of the range of the ironing board in order to permit movement of the iron to any place within the range of the board.

To use the ironer, the operator may sit down on a chair in front of the board, the pointed end of the board being to the left of the operator and the jointed arm to the right. The iron may then be brought down on the work by pressing with the foot on the foot pedal 70. This brings the weight of the iron on the work and by grasping the handle it may be moved over the work without any effort. No exertion has to be exercised in lifting or tilting it to any point. All that is necessary is to relieve the pressure on the foot pedal to bring it partially or entirely up above the work. During the ironing with the foot pedal held down, the weight of the iron rests on the work. The supporting collar below the handle bracket automatically drops down when the weight of the iron rests on the board, thus signalling to the operator that the iron is in its effective operating position. The ironing handle is high above the iron and remains cool while used, although the iron develops much more heat than an ordinary iron. By swinging the iron to the side, the entire board is clear for placing new work on the board and it is not necessary to lift the iron to get it out of the way. Since the iron has a large base, 5 inches wide and 8½ inches long, the ironing may be done very fast. Should the operator suddenly leave the board, the iron is automatically lifted from the work, and the damage of burning any articles that are ironed is eliminated.

After the ironing work is finished, the legs and the foot rod may be folded against the board and the entire device stored in a closet. To unfold the device for use, it is placed upright, as shown

in Fig. 4, with the weight resting on the front legs. The rear legs are then unfolded and the device can be rested on the rear legs while the front legs are being unfolded. This is done by swinging the front legs back until they strike the stop in the way shown in Fig. 8 whereupon the legs are shifted sideways in the position shown in Fig. 7 and then swung forward to the position shown in Fig. 5. The foot lever which is held by the spring 71 against the board is then pulled down and the device is ready for ironing.

In Fig. 14 is shown an ironing device having a modified form of lifting mechanism. As in Fig. 1, the mechanism has a supporting sleeve 100 which is jointed to a supporting bracket 101 by links 102, 103. One of the links is provided with a lever arm extension 104 which is pressed by a compression spring 105 to hold the sleeve 100 in the upper position shown in Fig. 14 in which the cantilever arm 110 supports the iron in lifted position above the ironing board. A cord 111 leading from the end of the lever 104 and over a roller 112 on the underside of the board to a stirrup 113 controls the movement of the sleeve. By applying downward foot pressure to the stirrup 113, the cord 111 pulls the lever 104 against the force of the spring 105 to the position indicated by the dotted line 114 in which the cantilever arm 110 lowers the iron and places its weight on the board. If the pressure on the stirrup 113 is released, the compression spring 105 forces the lever 104 to its downward position shown in Fig. 14 lifting the iron from the board. This device has no foot lever, and the cord with the stirrup may be placed at any place convenient to the operator. The cantilever arm 110 with the enclosed cord 115 may be removed from the sleeve to facilitate the storing of the board.

In Fig. 15 is shown another modification of the invention in which the jointed cantilever arm 120 which supports the iron has a downwardly extending tubular extension 121 rotatably fitting into a socket sleeve 122 attached by a bracket 123 to the underside of the ironing board 30. The tubular extension 121 is provided with a supporting ridge 125 fitting into the interior of the sleeve 122 and is pressed upwardly by a helical compression spring 126 located within the sleeve. Normally the tubular extension 121 and the iron carried by arm 120 are in lifted position, the upward movement of the arm extension 121 being limited by a collar 127 attached to the upper end of the sleeve 122. Through the hollow interior of the tubular arm extension 121 extends a rotatably mounted pull rod 128 which can be rotated within the sleeve to bring its foot lever 129 within the reach of the operator standing or sitting in front of the board. On pressing against the foot lever 129, the pull rod 128 pulls the sleeve 121 against the force of the compression spring 126 to a downward position till the iron is brought down on the ironing board as in the prior devices. To permit storing of the ironing device, the foot arm 129 has a hinge connection 129' shown in detail in Fig. 16, permitting the folding of the lever 129 against the board 30.

In Figs. 17 and 18 is shown a further modification of the invention in which the lifting mechanism similar to that shown in Fig. 14 is actuated by a small electromagnet constituting a part of the actuating mechanism for lowering the iron. The mechanism comprises a supporting bracket 140 which carries on a channel member 141 two links 142, 143 by means of which the supporting sleeve 144 in which the extension 145

of the freely swinging cantilever arm 146 with its hinged forearm 147 are seated to permit lifting and lowering of the iron. To move the lever 142 to its downward position indicated by the dotted line 149, there is provided a solenoid magnet 150 having a stationary core 151 attached to the bracket and a movable plunger 152 actuated by an exciting winding 153. The lower end of the plunger 152 has a pin 155 engaging slots 156 of a lever 157 extending from the link 142 so that upon energizing the exciting coil 153 of the magnet the plunger 152 and the lever 147 are pulled to the upward dotted line position, thereby lowering the supporting arm 146 and placing the weight of the iron on the board as in the prior devices.

In order to keep the supporting arm 146 and the iron in the raised position, the lever 157 is provided with lateral extensions 160 and two compression springs 162 mounted between the lever extensions 160 and the top 163 of the supporting bracket 140, the compressed springs 162 being sufficiently strong to exercise a force which holds the lever 157 and the supporting mechanism in the full line position shown in Fig. 17. The electromagnet 150 is so designed that when energized in the position in which the plunger 152 is in its lowermost position shown in Fig. 17, the magnet force acting on the plunger will be sufficient to pull the plunger 152 toward the stationary core 151 against the action of the compression springs 162 until the sleeve 144 with the iron arm 146 are lowered placing the weight of the iron on the ironing board. As the plunger 152 travels toward the core 151, the magnetic force increases and reaches a value required to keep the lever in its upward dotted line position against the full opposing force of the compression spring 162. Since the magnetic gap is at a minimum in the upper position of the plunger 152, a relatively small electromagnet is able to supply the entire force required to overcome the counteracting force of the spring, which is not opposed by the weight of the iron when the iron rests on the board.

The magnet winding 153 may be energized from the main supply cord 170 that delivers current for heating the iron by a branch cord 171 having a control branch 172 leading to a foot actuated contact switch 173 for energizing the magnet circuit only as long as the foot rests on the switch button 173. On placing the foot on the switch button 173, the iron is lowered to its operative ironing position, and the instant the contact button 173 is released the iron is lifted to its floating position above the board.

The compression springs 16 with the associated operating elements constitute a compact unit supported on the bracket 140 and may be enclosed in a casing 180. The unit may be mounted on the underside of the ironing board or may be independently supported on a separate pedestal, such as a tripod, having a supporting member 181 to which the casing 180 with the lifting mechanism may be clamped by wing screws 182, and folding legs 183, 184 suitably joined to the supporting member to hold the lifting mechanism with the supporting arm 146 adjacent the ironing board.

With the ironing device of the invention, it is possible to iron much faster than with a hand iron because the large weight of the iron is much more efficient in ironing and there is no lost time and no lost motion in lifting the iron back and forth from the work. The operator is relieved

of the work of lifting the iron and bringing it from one part of the board to another for placing new work on the board. Since the operator sits while ironing, he can accomplish much work in a very efficient way. The iron may be readily tilted to iron lacework, folds, and to perform special operations without imposing a strain on the operator. Throughout the operation the iron handle is cool and troubles with the cord are eliminated. By keeping the plug socket at a distance from the hot iron, the plug terminals and lead connections are maintained at a low temperature, reducing the resistance and the heating of the contacts and preventing their deterioration. The special shape of the iron with its beveled edges make it possible to bring the iron under buttons and the long nose of the iron gets easily under sleeves, collars and similar places which are hard to reach. The large surface of the iron makes possible ironing with fewer strokes and eliminates ridges and marks occurring with smaller irons.

The principles of invention disclosed herein will suggest many modifications thereof to those skilled in the art, and it is accordingly desired that the appended claims be given a broad construction commensurate with the scope of the invention.

I claim:

1. In an ironing device for ironing articles on an elevated oblong ironing board having a corner portion at one end, an iron, pivotal supporting means including lifting means for lifting said supporting means carried by said board adjacent the corner portion of said board on the underside thereof, a cantilever arm extending from said supporting means having a free end carrying said iron above the level of said board, and foot-actuated operating means carried on the underside of said board for actuating said lifting means to lower said iron to the level of said board upon actuation of said operating means and for lifting said iron above the level of said board upon releasing said operating means, said cantilever arm consisting of a plurality of articulated hollow tubular members shaped and proportioned to permit free continuous movement of said iron over the area of said board including the region overlapping the circumference of said board while resting on the board and folding of said arms substantially within the area of said board adjacent the level of the board.

2. In an ironing device for ironing articles on an elevated oblong ironing board having a corner portion at one end, an iron, supporting means including lifting means for lifting said supporting means carried by said board adjacent the corner portion of said board on the underside thereof, a cantilever arm formed of two articulated hollow tubular arm sections pivotally carried by said supporting means and having a free end carrying said iron above the level of said board, and foot-actuated operating means carried by the underside of said board for actuating said lifting means to lower said iron to the level of said board upon actuation of said operating means and for lifting said iron above the level of said board upon releasing said operating means, one of said hollow arm sections having a curved portion shaped and proportioned to permit free continuous movement of said iron over the area of said board and the region overlapping the entire circumference of said board except the support corner of said board while resting on the board and in a higher level above the board and

5 folding of said arms substantially within the area of said board adjacent to the level of said board.

3. In an ironing device for ironing articles on an elevated oblong ironing board having a corner portion at one end and foldable supporting legs, an iron, a pivotal support including lifting means for lifting said support carried on the underside of said board secured to the corner portion of said board, a cantilever arm formed of two articulated hollow tubular arm sections pivotally carried by said supporting means and having a free end carrying said iron above the level of said board, and operating means carried by said board on the underside thereof for actuating

10 15 said lifting means to lower said iron to the level of said board upon actuation of said operating means and for lifting said iron above the level of said board upon releasing said operating means, said supporting means, said operating

20 means and said cantilever arm sections being shaped, proportioned and correlated to said board and its legs to permit free movement of said iron over the area of said board while resting on the board and in a higher level above the board and

25 folding of said arms within the area of said board adjacent the level of said board while said legs are folded against said board for enabling the storing of said board and the elements carried by it in a fraction of the space occupied by the

30 board and its unfolded legs.

4. In an ironing device for ironing articles on an ironing board, an iron, a pivotal support carried by said board at one side of said board,

5 a cantilever arm formed of two articulated hollow tubular arm sections pivotally carried by said support and having a free end carrying said iron above the level of said board, and electrically actuated operating means carried by said board for lowering said support to a level at which the weight of said iron is carried by said board upon energizing said operating means and for lifting said iron above the level of said board upon de-energizing said operating means, said cantilever arm sections being shaped and proportioned to permit free movement of said iron over the area of said board while resting on the board and in a higher level above the board and folding said arm sections substantially within the area of said board.

5. In an ironing device for ironing articles on a work support, an iron, guide means for loosely carrying and guiding said iron over the work support above the level of said work support, foot actuated operating means for actuating said guide means to lower said iron to a level at which the weight of the iron is released to rest on said work support, and indicating means associated with said iron and said guide means actuated by the motion of said iron relatively to said guide means upon releasing of said iron when the entire weight of the iron is carried by said work support for visually indicating that the weight of said iron rests on said work support and controlling the force applied to said guide means.

SIMON DEUTSCH.
